(57) **CLAIM**

The ornamental design for a cooler, as shown and described.

DESCRIPTION

FIG. 1 is a front, right side perspective view of a cooler showing my new design.

FIG. 2 is a top plan view thereof.

FIG. 3 is a front view thereof.

FIG. 4 is a rear view thereof.

FIG. 5 is a bottom plan view thereof.

FIG. 6 is a right side view thereof; and,

FIG. 7 is a left side view thereof.

The solid lines in FIGS. 1-7 illustrate a cooler according to the present invention. The broken lines in FIGS. 1-7 are for illustrative purposes only and form no part of the claimed design.
